CLAIM

The ornamental design for a tool handle, as shown and described.

DESCRIPTION

FIG. 1 is a front elevational view of a tool handle, showing my new design;

FIG. 2 is a top, front perspective view thereof;

FIG. 3 is a front elevational view of detail “3” identified in FIG. 1, shown enlarged for clarity of disclosure;

FIG. 4 is a left side elevation view of a tool handle, shown in a condition of use; and,

FIG. 5 is a top plan view.

In the drawings, the broken lines depict environmental matter that forms no part of the claimed design.
